UNITED STATES PATENT OFFICE.

ASAJIRO FUJIWARA, OF WINNIPEG, MANITOBA, CANADA.

AUTOMOBILE SIGNALING APPLIANCE.

1,372,415.

Specification of Letters Patent. Patented Mar. 22, 1921.

Application filed July 5, 1917, Serial No. 178,748. Renewed September 20, 1920. Serial No. 411,561.

To all whom it may concern:

Be it known that I, ASAJIRO FUJIWARA, of the city of Winnipeg, in the Province of Manitoba, Canada, have invented certain new and useful Improvements in Automobile Signaling Appliances, of which the following is the specification.

The invention relates to a signaling appliance for automobiles and the object of the invention is to provide a simple attachment which can be readily applied on the front of an automobile and manipulated by the driver to indicate, either by day or night, the direction of travel of the car thereby allowing an observer to determine the course of the car and thereby avoiding accident.

A further object is to provide an attachment whereby a driver can readily indicate to one controlling the traffic the direction in which he wishes to proceed.

With the above general objects in view the invention consists essentially in the arrangement and construction of parts hereinafter more particularly described and later pointed out in the appended claims, reference being had to the accompanying drawings in which:—

Figure 1 represents a rear view of the complete appliance.

Fig. 2 represents an enlarged detailed vertical sectional view through one end of the casing of the appliance showing the interior working parts.

Fig. 3 represents an enlarged detailed vertical sectional view through the central portion of the casing of the appliance showing the interior working parts.

Fig. 4 represents an enlarged detailed vertical sectional view through the casing, the section being taken in the plane denoted by the line X—X' Fig. 2.

Fig. 5 represents a horizontal sectional view through one end of the casing, the section being taken in the plane denoted by the line Y—Y' Fig. 2.

Fig. 6 represents a vertical sectional view through one end of the casing, the section being taken in the plane denoted by the line Z—Z' Fig. 2.

Fig. 7 represents an enlarged detailed horizontal sectional view through the central portion of the casing, the section passing through the hand wheel.

Fig. 8 represents a plan view of the hand wheel and adjacent sleeve.

Fig. 9 represents a vertical sectional view

through the sleeve, the section being taken in the plane denoted by the line T—T' Fig. 7.

Fig. 10 represents diagrammatically the electrical circuits.

In the drawings like characters of reference indicate corresponding parts in the several figures.

1 represents an elongated box like casing 65 having the ends thereof terminating in two upstanding extensions 2 and 3 of a peculiar shape to accommodate parts later disclosed. This casing is designed so that it can be mounted on the front end of an automobile 70 such as the wind shield, in which position it is desirable that the end extensions of the casing appear at the opposite sides of the wind shield.

The extensions 2 and 3 house in each instance a side swinging indicator or pointer in the nature of a hand 4 and a front swinging indicator or pointer in the nature of a hand 5 and these indicators are arranged so that they can be controlled in their swinging movement by the driver of the car.

The hand 4 in each instance is normally contained within the extension which is provided at the side with a side slit 6 to allow the hand to swing out, while the hand 5 is 85 normally pocketed within the front side of the extension which is depressed at 7 to receive the hand.

Each indicator 4 is mounted on a cross shaft 8 having bearings in the side of the casing and on the shaft to the side of the hand 1 mount a partial gear 9 which cooperates with parts shortly described to manipulate the hand.

The hand 5 in each instance is mounted on 95 a shaft 10 passing lengthwise of the casing and suitably mounted therein which shaft carries a combined operating and switch controlling lever 11 exposed to the exterior of the casing and fitted with a finger piece 100 12 whereby the lever can be readily manipulated.

Catches 13 and 14 are mounted on the casing and engage with the levers to prevent the same from moving until the catches are 105 released as it will be obvious from the construction shown that unless something of this nature was supplied the hands 5 could fall forwardly under the action of gravity.

Centrally of the casing I locate a sleeve 110 15 in which I mount rotatably a socket 16 provided with an extending shank 17 which

terminates in a controlling hand wheel 18 located at the end of the sleeve. The socket has the opening therein square in cross section to receive slidably the square axle 19 of 5 a controlling gear wheel 20 contained within the casing. A spring 21 is interposed between the outer end of the sleeve, which is closed, and the socket which spring operates to hold the hub 18' of the hand wheel normally against the closed end of the sleeve 10 and with the lugs 22 formed on the end of the hub in receiving notches provided in the end of the sleeve.

According to this arrangement it will be 15 obvious that under normal conditions the hand wheel as well as the gear will be locked against rotation but yet the hand wheel can be turned to operate the gear wheel when wished.

20 A rack bar 23 is mounted in the underside of the casing and is provided more or less centrally with rack teeth 24 engaging with the teeth of the gear 20 and at the ends with rack teeth 25 and 26 which are adapted to 25 engage with gear wheels 27 and 28 rotatably mounted on cross axles 27' and 28' carried by the side of the casing. The arrangement of the rack teeth 25 and 26 in respect to the gear 27 and 28 is such that when the rack 30 bar is shifted in one direction the teeth 25 pass into mesh with the gear wheel 27 while those 26 pass away from the teeth of the gear 28 and vice versa.

29 and 30 represent further independent 35 rack bars slidably mounted in the top part of the casing and provided adjoining the gear wheels 27 and 28 with rack teeth 29' and 30' and at their outer ends each with rack teeth 31 engaging with the teeth of the 40 partial gears 9.

From the above disclosure it will be obvious that if one turn the hand wheel in a clockwise direction the rack bar 23 will move to the left and in moving will turn the gear wheel 28 but not that 27 and in turning the gear 28 will move the rack bar 30 endwise and to the right and by so doing 45 will cause the rotation of the partial gear 9 at the right hand end of the casing in a direction which will swing the hand 4 at the right hand end of the casing out and down.

In order to arrest any undue movement 50 of the gears 27 and 28 I have provided arresting springs 32 and 33 which play on the surface of the gears at all times.

The device as above described is quite sufficient for use by day as the hands can be readily seen and the driver of the car can, by manipulating the hands, indicate the direction 60 in which he wishes to travel, that is to say, if he wishes to turn to the left he manipulates the hand wheel to swing down the hand 4 at the left, if he wishes to turn to the right he turns the hand wheel to throw down 65 the hand 4 at the right and if he wishes to

go straight ahead he indicates this by swinging down one or other of the hands 5 as the circumstance requires.

For use by night it is desirable to illuminate the hands and this is done in the following way:—

In the upper part of each extension an electric lamp indicated generally at 34 is inserted and suitable openings are provided in the extension to allow the lamp when 75 illuminated to illuminate ahead and to the side provided the hands are down.

Two lead wires 35 and 36 pass to the casing from a suitable source of electromotive-force and the lights are wired in parallel across the mains. Push switches indicated generally by the reference numerals 37 and 38 are mounted in the casing and inserted in the separate light circuits, these switches allowing of the separate control of 85 the lights.

In order to effect the illuminating of the lights coincident with the manipulation of the hands I have supplied each of the rack bars 29 and 30 with a striker indicated at 90 39 and these strikers are designed in the movement of the rack bars to engage with and close the switches.

I have not considered it necessary to enlarge on the detail of what I have termed a 95 push switch as this forms no part of my invention. Any kind of switch can be utilized to close the circuit at the proper time and in the manipulation of the rack bars.

The switches just disclosed only operate 100 to close the circuit when the hands 4 are swung out. Other switches in circuit with the lamps and associated with the levers 11 are supplied so that when the levers are manipulated to throw down the hands 5 the 105 lamps will be illuminated. These switches indicated at 40 are simply contact bars 41 inserted in the light circuits and adapted when engaged by strikers 42 formed as part 110 of the levers to close the light circuits.

At this point it is to be remembered that the hands 5 are swung down by pulling the levers 11 outwardly and upwardly and according to the arrangement shown best in Fig. 4 when the levers are in their upper 115 position (see dotted outline Fig. 4) the strikers will hit the contact bars and close the circuit.

When one is using my appliance in the day time the circuit will be opened by manipulating a main switch 43 (see Fig. 10) so that in the manipulation of the appliance the lights will not work. However, at night, by turning on the switch 43, one will have a light illuminated each time a hand is manipulated.

What I claim as my invention is:—

1. An automobile signaling appliance comprising a casing passing laterally across and forwardly of the automobile and terminat- 130

ing in vertically disposed end extensions having each an open outer side, a hand like indicator pivotally mounted in each extension and outwardly and downwardly swingable through the side opening, a hand controlled wheel located centrally of the casing, a gear wheel contained within the casing and turning with the controlling wheel, a rack bar passing lengthwise of the casing and having centrally disposed rack teeth thereon engaging with the gear wheel and having rack teeth located at the outer ends thereof, gear wheels rotatably mounted in the casing and meshing with the latter rack teeth respectively, a pair of rack bars extending lengthwise of the casing and provided with rack teeth engaging the latter gear wheels and provided at their outer ends with rack teeth entering the bases of the end extensions and partial gear wheels engaging with the latter rack teeth and secured to the hand like indicators.

2. A signal comprising an elongated casing having a vertical extension at each end, a signal member pivoted in each extension,

and means for selectively operating said signal members comprising a toothed gear mounted in the casing between the extensions and provided with a square shank extending centrally from one side thereof, a sleeve extending outwardly from the casing and alined with said shank, a socket member receiving the shank therein and slidably mounted in said sleeve, a hand wheel carried by the outer end of said socket member, resilient means engaging the socket member and yieldably holding the hand wheel against the outer end of said sleeve, and complementary locking means carried by the sleeve and said hand wheel whereby the latter is normally held against rotation and operative connections extending between said gear and each of said signal members.

Signed at Winnipeg, this 14th day of June, 1917.

ASAJIRO FUJIWARA.

In the presence of—
GERALD ROXBURGH,
ROLAND FOSTER.
